UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

DIE-SEPARATING MEANS.

Application filed April 25, 1924. Serial No. 708,891.

To all whom it may concern:

Be it known that I, RICHARD LESTER WILCOX, a citizen of the United States, residing at Waterbury, in the county of New Haven and State of Connecticut, have invented certain new and useful Improvements in Die-Separating Means, of which the following is a specification, reference being had therein to the accompanying drawings.

10 My invention relates to die separating means, its principal object being to provide simple mechanism for separating the dies of an open die header or upsetting machine.

15 Among other aims and objects of my invention may be recited the provision of a device of the character mentioned with a view to compactness and in which the number of parts are few, the construction simple, the cost of production small, and efficiency and operation high.

20 The improvements in the details and arrangement of parts will be apparent from an inspection of the accompanying drawings, in connection with the description 25 hereinafter contained, and wherein an embodiment of the invention is disclosed for the purpose of imparting a full understanding of the same.

Having more particular reference to the 30 drawings and in connection with which like reference characters refer to corresponding parts in the several figures;

Figure 1 is a front elevation of a pair of dies for a heading machine or the like and 35 the adjacent supporting mechanism therefor with my improved separating means connected therewith;

Figure 2 is a side elevation thereof partly in section;

40 Figure 3 is a modified form of a detail of my improved mechanism;

Figure 4 is a fragmentary front elevation, partly in section, of my improved mechanism as applied to the under side of 45 the dies; and the parts thereof in section being taken generally upon line 4—4 of Figure 5;

Figure 5 is a side elevation of Figure 4. It has heretofore been the practice to 50 separate the dies of an open die header or upsetting machine at the wire feed line by parting pins, separating pins or the like, an illustration of such means being shown in Letters Patent No. 1,104,090, dated July 21,

1914, particularly in Figure 4 thereof, and 55 also in Letters Patent No. 1,108,958, dated September 1, 1914, a heavy flat spring, not shown in either of the above patents, bearing upon the upper end of each of the parting pins or separating pins, which move in 60 a path at substantially a right angle to the movement of the dies. With such mechanism the die cap or other part or parts that support the pins must be machined with great care and exactness and each must be 65 in correct alignment with each other and the groove formed by the angular corner faces of the dies, when the dies are in proximity to the wire feed line. If the pins are not so arranged, the lower pointed end thereof will 70 not register with said groove, thus having a tendency to cramp the dies and apply an unequal pressure thereto at different points throughout their length. If this occurs, the dies may be separated more at one end than 75 at the other, and if perchance the minimum separation is at the inner end of the dies a defective feed of the wire results and the end of the wire may abut against the dies 80 and stop the feed.

As the pins are of substantial length the element in which they are mounted must of necessity be of substantial height to provide proper support therefor and this height, as well as the pin operating springs, requires 85 space that can otherwise be advantageously utilized.

All of the above and other objections of the heretofore conventional method for separating the dies are obviated in my improved device, which occupies the minimum amount of not otherwise required space, the necessity of fine machining of the parts is entirely eliminated, and in these, and many other ways, produces results that are advantageous and insure certainty and efficiency in operation, and with mechanism that is of comparatively simple design.

Having more particular reference to the drawings, numerals 10 and 11 represent the dies, which are of the usual form with corner angular faces 12 which unite to form a V-shaped groove substantially as shown in Figures 1 and 3, wherein the dies are near the wire feed line. A piece of wire designated 13 is shown in section at this wire feed line.

The bed plate upon which the dies are

supported is designated 14, and the cap or cover over the top thereof 15.

All of the mechanism above described is of a well known form and operates in an 5 equally well known manner and therefore needs no further description herein.

The means for actuating the dies is not shown herein for the above reason, but the same travel between the said wire feed line 10 and the upsetting line, which latter line is designated α — α in Figure 1. From the wire feed line to the upsetting line the dies are positively actuated by relatively powerful mechanism to cut off a piece of the wire rod 15 but are usually returned from the upsetting line by spring mechanism.

As shown, the dies are held against end-wise movement in the supporting means by the plates 16 and 17, this being only one of 20 the many ways by which the same result may be accomplished.

Within the cover 15 are one or more grooves 20 in each of which is a lever 19 that is hinged at one end upon a stud 18.

25 Movable within the cover 15 are plungers 21, corresponding in number with the levers 19, and each of which is surrounded by a coil spring 22 within the bore 23. These plungers are limited in their downward movement by the nuts 24 threaded on the shank thereof, thus providing means to vary the relative position of the plungers and the tension of the springs 22.

Resting within the V groove formed by 35 two of the angular faces at the corners of the dies is a roll 25 or block 26 triangular in cross section, two of the angular faces of which are in contact with the angular corner faces of the dies 10 and 11 and the other 40 face with the underside of the lever 19. As the dies travel from the wire feed line to the upsetting line, the roll 25 or the block 26 travel with the dies and as the adjacent faces of the dies are brought into contact 45 with each other are moved slightly upward, the lever 19 swinging upon its pivot mounting to permit this action. During the return movement, that is, as the dies approach the wire feed line, the spring 22, through the 50 lever 19 moves the roll 25 or the block 26 downwardly into the V grooves formed between the dies, which action separates the dies sufficiently to permit the wire rod to pass therebetween.

55 In Figures 1, 2 and 3, I have shown my improved mechanism as applied to the top of the dies, but it will operate equally as well if applied to the under side thereof, or if desired, to both the top and bottom.

60 In Figures 4 and 5, the invention is illustrated as applied to the under side of the die, in which case, the stud 18 is preferably connected with the bed plate 14^a or other part below the dies, and the lever 19 is 65 moved in one direction by a spring 27, which

exerts its tension against the hollow plug 28. The die cap or cover 15^a is, of course, modified slightly in this embodiment of my invention. In all other respects, however, the mechanism is constructed and operated in 70 the same manner as if applied to the top of the dies. If desired the mechanism may be applied to both the top and bottom of the die in which case the structures as shown in Figures 1, 2, 4 and 5 are utilized. 75

There are minor changes and alterations that may be made within my invention, aside from those herein suggested, and I would therefore have it understood that I do not limit myself to the exact construction herein shown and described, but claim all that falls fairly within the spirit and scope of the appended claims. 80

Having described my invention, what I claim as new and desire to secure by Letters 85 Patent is:

1. In combination with the dies of a heading machine or the like, having faces thereon which co-operate to form a groove when the dies are adjacent to each other; of 90 means for holding the same; and means for separating the dies at a predetermined station, comprising a lever, yielding means for the lever, and a member in the groove independent of the lever having a movable contact therewith and moved in one direction thereby. 95

2. In combination with the dies of a heading machine or the like, having faces thereon which co-operate to form a groove when 100 the dies are adjacent to each other; of means for holding the same; and means for separating the dies at a predetermined station, comprising a lever, yielding means for the lever, and a member in the groove independent of the lever having a movable contact therewith and moved in one direction thereby, the mounting of the lever being upon one side of the wire feed line. 105

3. In combination with the dies of a heading machine or the like, having faces thereon which co-operate to form a groove when the dies are adjacent to each other; of 110 means for holding the same; and means for separating the dies at a predetermined station, comprising a lever, yielding means for the lever, and a member in the groove independent of the lever having a movable contact therewith and moved in one direction thereby, the yielding means being upon one 115 side of the wire feed line.

4. In combination with the dies of a heading machine or the like, having faces thereon which co-operate to form a groove when the dies are adjacent to each other; of 120 means for holding the same and means for separating the dies at a predetermined station comprising a lever, yielding means for the lever; and a member in the groove independent of the lever having a movable con- 125

tact therewith and moved in one direction thereby, the mounting of the lever being upon one side of the wire feed line and the yielding means being upon the other side thereof.

5. In combination with the dies of a heading machine, or the like, having faces thereon which co-operate to form a groove when the dies are adjacent to each other; of
10 means for holding the same, comprising a supporting member and a cap or cover; and means for separating the dies at a predeter-

mined station, comprising a lever, yielding means for the lever, and a member in the groove independent of the lever having a 15 movable contact therewith and moved in one direction thereby, the lever being mounted in the underside of the cap or cover, the mounting of the lever being upon one side of the wire feed line and the yielding means 20 being upon the other side thereof.

In testimony whereof, I have hereunto affixed my signature.

RICHARD LESTER WILCOX.
